UNITED STATES PATENT OFFICE.

JOHANNES JACOBUS WEYERMAN, OF ROTTERDAM, NETHERLANDS.

REMOVABLE ELEVATOR.

Application filed August 11, 1921. Serial No. 491,330.

To all whom it may concern:

Be it known that I, JOHANNES JACOBUS WEYERMAN, guild inspector, subject of the Queen of the Netherlands, residing at Rotterdam, Netherlands, 58 Schoonebergeweg, have invented certain new and useful Improvements in Removable Elevator, of which the following is a specification.

The subject of the invention is a removable elevator, the top of which is capable to be folded back, the side view having the form of an isosceles triangle along one of the sides of which a goods platform runs, this elevator possessing moreover a simple construction which opens a possibility of goods being able to be rolled or pushed from the ground on to the platform that can be let down, without the elevator showing any inclination to go backwards.

After folding back the top, the apparatus is capable of being easily introduced under low rafters, driving belts, electric cables etc., while the triangular form of the frame increases the stability of the arrangement. For preventing the apparatus running away when goods are rolled or pushed from the ground on to the platform, the whole arrangement is supported by means of a running axle introduced in the centre and by the introduction at one side of the axle of one or more screw-jacks, by screwing of which the arrangement can be tilted over on that axle till it is standing firmly on the ground.

For clearness sake, the arrangement, as an example, is further described on the drawing.

Figure 1 is a front view;

Figure 2 is a side view with the folding top up, and

Figure 3 is a side view with the folding top down.

In these illustrations, 1 is the upright

frame, 2 is the folding top, 3 is the goods platform and 4 the axle with wheels, by means of which the arrangement can be moved and upon which it can be tilted over to be fixed. To this purpose screwjacks, indicated at 5, are constructed on the floor joists. When the elevator is in use, these screwjacks are screwed down till the opposite end of the floor (platform side) touches the ground; so the elevator stands firmly on the ground. The hoisting drum is indicated at 6; 7 is the hoisting cable that runs over a pulley 8, and 9 and 10 are corresponding holes through which a bolt can be inserted to fix the top in an upright position.

When the apparatus, standing firmly on the ground, has its top folded down and the hoisting cable put over a pulley fixed anywhere at the ceiling of the building, the apparatus may be used as a winch only.

Having now fully described my said invention, what I claim and desire to secure by Letters Patent is:

A portable elevator comprising a base portion and an upright frame, the upright frame having the form of an isosceles triangle in side elevation, a portion of said upright frame being hinged to fold downwardly along one of the sides of said triangle, a goods platform projecting laterally from said base portion, a wheeled axle extending transversely across substantially the centre of said base portion and a screw jack located to one side of said centre whereby the elevator may be tilted about the axis of said axle to secure the elevator in a stable position.

In testimony whereof I have affixed my signature in presence of a witness.

JOHANNES JACOBUS WEYERMAN.

Witness:

S. NELL.
